UNITED STATES PATENT OFFICE.

FRED WESLEY WRIGHT, OF HUNSLET, LEEDS, ENGLAND, ASSIGNOR TO GEORGE MANN & COMPANY, LIMITED, OF LARCHFIELD WORKS, LEEDS, ENGLAND.

PRINTING MACHINE.

Application filed January 26, 1927, Serial No. 163,810, and in Great Britain February 1, 1926.

The invention relates to devices used for tensioning printing plates, rubber blankets or sheets of other material in different types of printing machines.

5 The main difficulties met with in the design of devices of the kind indicated are to secure an adequate purchase with an irreversible mechanism and also to provide for a quick release of the blanket, sheet or 10 the like.

With the main object of providing an improved mechanism having the desired characteristics, the present invention consists in 15 the combination of elements hereinafter described and particularly pointed out in the claims.

Referring to the accompanying drawings:—

Figure 1 shows an end view of one form 20 of the invention applied to a rotary machine,

Figure 2 being a corresponding side elevation, while

Figure 3 shows an end view of a modified 25 form of mechanism for engaging and disengaging the rack.

Corresponding parts in the different figures are denoted by the same reference numerals.

In carrying the invention into effect according to one form as shown in Figure 1, 30 the blanket, sheet or the like, 2, passing round the cylinder, 3, is secured to the usual transverse bar, 4, by any suitable means.

This bar is provided with a square, 5, at 35 one or both ends and also with a keyed pinion, 6, with which a rack, 7, gears. The rack is slidable in a bracket, 8, pivoted at 9 to the cylinder end (in the case of rotary machines) and is provided with a lug, 10,

40 projecting into a recess in the bracket, the lug being threaded for the reception of a fine-pitched threaded spindle, 11, having a nut, 12, at one end by which it can be turned and a pinned collar, 13, at the other end.

45 In the form of the invention shown, the bracket, 8, is moved into the rack-engaging position by a spring, 14, surrounding the rod, 15, pivoted at one end to the bracket, 8, and passing at the other end through a 50 staple, 16, in the cylinder end.

A screw-pin, 17, passing through a curved slot, 18, in the bracket serves to hold the latter against the cylinder end while permitting freedom of movement within the 55 desired limits.

According to a modified form of engaging and disengaging mechanism, (see Figure 3), two parallel-faced horns or lugs, 20, 20, are provided on the bracket, 8, and between them is arranged a circular disc, 21, with 60 flanges, 22, pivoted eccentrically at the point, 23. Operation of the hexagon, 24, in rigid association with the disc, 21, serves both to turn the bracket, 8, into the engaging or disengaging position and automatically to 65 lock it therein.

In order to operate the tensioning devices forming the subject of the present invention, the bracket, 8, with its rack, 7, is disengaged and the lug, 10, moved by means of the 70 threaded spindle, 11, to the limiting position shown in the figures. After attaching the blanket, 2, to the bar, 4, in any usual manner, the slack is taken up by operation of the square, 5, when the rack, 7, is re- 75 engaged and the fine adjustment actuated to give the blanket the required degree of tautness.

Although certain specific forms of the invention have been described above, it will be 80 understood that variations from such forms may be made without exceeding the scope of the invention as set forth in the claims appended hereto.

Having now described my invention, what 85 I claim as new and desire to secure by Letters Patent is:—

1. A blanket tensioner for printing machines, comprising in combination, a blanket carrier; a blanket bar rotatable on said carrier; means for rotating said bar; together with means for engaging and disengaging said bar-rotating means at will. 90

2. A blanket tensioner for printing machines, comprising in combination, a blanket carrier; a blanket bar rotatable on said carrier; a gear co-axial with said bar and in driving relation thereto and means for operating said gear, said means including a second gear; together with means for carrying said second gear, said gear-carrying means being movable on said blanket carrier to engage and disengage said second gear at will. 95

3. A blanket tensioner for printing machines, comprising in combination, a blanket carrier; a blanket bar rotatable on said carrier about a certain centre; a gear co-axial with said bar and in driving relation thereto and means for operating said gear, said 100 105 110

means including a second gear; together with means for carrying said second gear, said gear-carrying means being pivotally mounted on said blanket carrier about a centre other than the said centre of said blanket bar.

4. A blanket tensioner for printing machines, comprising in combination, a blanket carrier; a blanket bar rotatable on said carrier; a gear co-axial with said bar and in driving relation thereto and means for operating said gear, said means including a second gear; means for carrying said second gear, said gear-carrying means being pivotally mounted on said blanket carrier; together with a single instrumentality for positioning and locking said gear-carrying means.

5. A blanket tensioner for printing machines, comprising in combination, a blanket carrier; a blanket bar rotatable on said car-

rier; means for rotating said bar including engaging gears; a bracket on which one of said engaging gears is mounted, said bracket being pivotally mounted on said carrier; together with parallel horns on said bracket and an eccentric operatively disposed between said horns for positioning and locking said bracket.

6. A blanket tensioner for printing machines, comprising in combination, a blanket carrier, a blanket bar rotatable on said carrier; a pinion in rigid association with said bar; a bracket pivotally mounted on said carrier; a rack gearable with said pinion and slidable on said bracket; together with means for traversing said rack in said bracket.

In testimony whereof I have signed my name to this specification.

FRED WESLEY WRIGHT.
